SUBMARINE BOAT.

1,164,394.

Specification of Letters Patent. Patented Dec. 14, 1915.

Application filed April 16, 1915. Serial No. 21,870.

To all whom it may concern:

Be it known that we, CONRAD REGENBOGEN and HANS VOGEL, citizens of the German Empire, residing at Kiel-Gaarden, 5 Germany, and Kiel, Germany, have invented certain new and useful Improvements in Submarine Boats, of which the following is a specification.

The present invention relates to submarine boats which are driven by a steam engine during surface travel, but by an electric motor when under water, and it resides primarily therein that the blasting plant for generating the combustion pressure air for 15 the boiler combustion is arranged outside of the pressure proof body of the boat.

In the accompanying drawing, one embodiment of the invention has been illustrated, and the figure shows a vertical longitudinal section through the boiler chamber, as well as portions of the adjacent chambers of a submarine boat of the above described kind.

A represents the pressure proof body of 25 the submarine boat and B a platform constructed as a superstructure which can be flooded when the boat dives down.

Within the boat is formed a boiler room C by the bulk heads a^1 a^2 , and this room is 30 reached by means of bulk head doors, not shown. In the room C a water tube boiler D, preferably an oil burning boiler, is inserted which generates the necessary steam for driving a steam engine, not shown. This 35 boiler is connected with a smoke stack E which penetrates through the pressure proof body A of the submarine boat, and the external portion thereof reaching above the platform is constructed to be laid down as 40 represented by dot and dash lines during submarine travel. The opening of the smoke stack may be closed water tight through a lid N, by means of a hand wheel n^1 from the room P adjacent to the boiler 45 room.

In the superstructure B, that is, outside of the pressure proof body A of the boat, is now, in accordance with the present invention, the blasting plant inserted, this plant 50 consisting of a ventilator F and a driving steam turbine G. The suction pipe H of the ventilator F opens outwardly, while the pressure pipe K penetrates through the pressure proof body A of the boat outside 55 of the boiler room C and from there leads

through the bulk head a^1 into the boiler room C. Through the assistance of a hand wheel l^1 , the pressure pipe K may be closed water tight from the room R through a closing valve L. From the same room the 60 starting and stopping of the driving turbine G for the ventilator F may also be operated by means of the steam throttling valve M through the hand wheel m^1 . This valve M can also be served from within the 65 boiler room C through the hand wheel m^2 for the purpose of regulating the blast. The rooms P and R may be connected with each other in a suitable manner through a passage, not shown, which may be closed 70 against the boiler room.

During surface travel, the parts have the position shown by full lines in the figure, that is the smoke stack E stands erect, the valve L is open and the steam valve N set 75 for running. The propulsion of the submarine boat then takes place through the steam engine fed from the boiler D, the blasting F G being in operation. If the boat is going to dive down, the boiler fire 80 is put out and the ventilator F stopped through the closing of the steam valve M. Thereupon the valve L is closed tightly by turning the hand wheel l^1 , the smoke stack E is laid down and the smoke stack lid N 85 closed by means of the hand wheel n^1 . The driving of the boat now takes place in a well known manner through an electric motor, not shown, fed from an accumulator battery. After the rising of the boat, a 90 temperature will exist in the boiler room C, in accordance with experience, when the boat has been under water for a great length of time, which does not permit of entering the room without danger. By 95 means of the described device it is now possible to open the lid N, to raise the smoke stack E, to unscrew the valve L and start the blasting plant F G from the adjacent rooms P and R. After a short time the 100 room C will be sufficiently cool so that it may be entered and the steam boiler again started for surface travel.

The arrangement of the blasting plant 105 outside of the pressure proof body of the submarine boat provides a considerable advantage in that this body of the boat is in this case not penetrated by the large suction pipe, but only by the small pressure pipe for the ventilator F. The pressure 110

proof body of the boat will therefore be less weakened and the closing valve L receives a smaller diameter which is very essential for a tight closing. Still another advantage is attained by passing the pressure pipe K through the pressure proof body A of the boat outside of the boiler room C, as at this place a complete tightening of the joint is possible at the point of penetration, because the portion of the body of the boat situated outside the boiler room will show a more uniform temperature than the portion thereof situated within the boiler room C which is exposed to considerable heat expansion and contraction in consequence of the different temperatures that occur therein, so that the tightening of the joints at the place of penetration is made very difficult.

20. We claim:—

1. In a submarine boat provided with a steam engine, a blasting plant for generating the combustion pressure air for the boiler, said blasting plant being situated outside of the pressure proof body of the boat.

2. In a submarine boat provided with a steam engine, and a pressure proof body, a blasting plant outside of said pressure proof body, a plurality of bulk heads within said body forming a water tight steam boiler room and separate operating rooms, a pressure pipe for the blasting plant through said pressure proof body into one of said operating rooms and from there through one of said bulk heads into said boiler room.

3. In a submarine boat provided with a steam engine, and a pressure proof body, a blasting plant outside of said pressure proof body, a plurality of bulk heads within said body forming a water tight steam boiler room and separate operating rooms, a pressure pipe for the blasting plant leading through said pressure proof body into one of said operating rooms and from there through one of said bulk heads into said boiler room, said boiler having a smoke stack penetrating through said pressure proof body, and means for closing said smoke stack, said means being actuated from within one of said operating rooms.

4. In a submarine boat provided with a steam engine, and a pressure proof body, a blasting plant outside of said pressure proof body, a plurality of bulk heads within said body forming a water tight steam boiler room and separate operating rooms, a pressure pipe for the blasting plant leading through said pressure proof body into one of said operating rooms and from there through one of said bulk heads into said boiler room, and means for closing said pressure pipe, said means being actuated from one of said operating rooms.

In testimony whereof the foregoing specification is signed in the presence of two witnesses.

CONRAD REGENBOGEN,
HANS VOGEL.
